UNITED STATES PATENT OFFICE.

JOSEPH SOSS, OF NEW YORK, N. Y.

INVISIBLE HINGE.

No. 825,943.

Specification of Letters Patent.

Patented July 17, 1906.

Application filed April 13, 1905. Serial No. 255,835.

To all whom it may concern:

Be it known that I, JOSEPH SOSS, a citizen of the United States, residing at New York, in the county of New York and State of New York, have invented certain new and useful Improvements in Invisible Hinges, of which the following is a specification, such as will enable those skilled in the art to which it appertains to make and use the same.

10 This invention relates to what are known as "invisible" hinges, which cannot be seen when the door or other article to which they are applied is closed; and the object thereof is to provide an improved device of this class which may be applied to an ordinary door, a gate, a sash, the cover of a piano, the cover of a box or case, or to any other article to which such devices can be applied, a further object being to provide an invisible hinge which is 15 simple in construction and operation and which is easily applied, and which is strong and durable and will not easily get out of order or need repair, and which may be made of any desired strength or capacity.

20 In addition to providing a hinge which may be applied to doors and other articles as above described, in which application one part of the hinge is secured to a stationary and the other to a swinging member, my improved hinge may be applied to two swinging parts or members, one of which is hinged to a stationary support or frame; but in the following description I will describe my improvement as applied to a door and door-frame, part of each of which is shown in the drawings, and in this application of my improved hinge or hinges the separate parts of said hinge or hinges are secured in what are called the "adjacent" surfaces of the frame 25 and door when the latter is in a closed position.

The invention is fully disclosed in the following specification, of which the accompanying drawings form a part, in which the separate parts of my improvement are designated by suitable reference characters in each of the views, and in which—

Figure 1 is a front view showing a part of a door-frame and door connected by one of my improved hinges, the door being in an open position; Fig. 2, a horizontal section on the line 2-2 of Fig. 1; Fig. 3, a section the same as Fig. 2, but showing the door in a closed position; Fig. 4, a section on the line 4-4 of Fig. 5 and showing the door in a closed position; Fig. 5, a section on the line 5-5 of Fig. 1; Fig. 6,

6, a view of the hinge detached and looking in the direction of the arrow *x* of Fig. 4; and Fig. 7, a view of the hinge detached and looking in the direction of the arrow *y* of Fig. 4, 6c part of the construction in Fig. 7 being also broken away.

In the drawings forming part of this specification I have shown at *a* what may be called a part of the door-frame and at *b* a part of a door; but it will be understood that the part *a* may represent any stationary member and the part *b* any swinging member, and in some cases both of said parts may be swinging members, and in the practice of my invention I provide a hinge comprising two separate similar parts, each of which in the form of construction shown consists of a yoke-shaped frame member or support *c*², having a face-plate *c*³. The yoke-shaped frame members or supports *c*² and the face-plates *c*³ are adapted to be countersunk in corresponding chambers or mortises in the stationary and swinging members *a* and *b*. The yoke-shaped frame members or supports *c*² are open at their 70 faces, and pivoted within said members, as at *d*, are curved plates or members *e*. These curved plates or members *e* are free to turn in and slide in the separate parts of the hinge which are countersunk in the stationary and 75 swinging members *a* and *b*, as hereinbefore described, and the movement of the plates or members *e* in the separate parts of the hinge are guided or controlled and limited by curved slots or grooves *c*⁶ in the top and bottom of the parts *c*² of the hinge, and by pins *e*², secured in the ends of the curved plates or members *e* and movable in the slots or grooves *c*⁶, or this construction may be reversed and the curved plates or members *e* 80 may be provided with slots or grooves, and the top or bottom of the part *c*² of the hinge, or both the top and bottom of said parts, may be provided with pins movable in said curved slots or grooves.

In the form of construction shown the bottom portion of the pivoted side of one of the curved plates or members *e* is cut away at its pivoted edge, as shown at *e*³ in Fig. 1, and the top portion of the other curved plate or member *e* is cut away at its pivoted edge, as shown at *e*⁴ in Fig. 1, and this forms projecting parts or hinged portions *e*⁵ on each of said members or plates which cross each other, as clearly shown in the drawings, and allow said plates or members *e* to move freely one upon another and to swing freely in a horizontal 100 105 110

plane. My invention, however, is not limited to the exact form and number of the swinging curved plates or members employed, and various changes in and modifications of these features of my improved hinge may be made without departing from the spirit of my invention or sacrificing its advantages.

With a hinge made in this manner it is possible for the swinging member to turn through an arc of one hundred and eighty degrees, and it will be observed that independent of the pivot-pins and guide-pins employed my improved hinge consists only of four parts in the form of construction shown, said parts comprising two frames, casings, or holders adapted to be secured in a stationary and a swinging member and curved plates or members pivoted in each of said frames, casings, or supports and adapted to swing in the other frame, casing, or support.

It will also be apparent that my improved hinge may be made of any desired size or strength and may be applied, as hereinbefore stated, wherever devices of this class are required.

Having fully described my invention, what I claim as new, and desire to secure by Letters Patent, is—

1. A hinge composed of two similar holders having parallel tops and bottoms, and curved swinging members pivoted between the tops and bottoms adjacent to the ends thereof and adjacent to the corresponding side edges thereof when the holders are placed face to face, the curved swinging member pivoted in each holder being adapted to turn freely within the other, and means for guiding the movements of said curved swinging members in said holders, substantially as shown and described.

2. A hinge composed of two similar holders having parallel tops and bottoms, and curved swinging members pivoted between the tops and bottoms adjacent to the ends thereof and adjacent to the corresponding side edges thereof when the holders are placed face to face, the curved swinging member pivoted in each holder being adapted to turn freely within the other, and means for guiding the movements of said curved swinging members in said holders, and for limiting the same, substantially as shown and described.

3. A hinge comprising two yoke-shaped casings having parallel tops and bottoms provided at their ends with oppositely-directed face-plates between which are openings similar in form and dimensions to the said holders in cross-section, and curved swinging

members pivoted within said openings adjacent to said face-plates and at the corresponding sides of the holders when the latter are placed face to face, the said curved swinging members being crossed and the curved swinging member which is pivoted in one holder being free to swing and turn in the other holder, and means for guiding the movement of said curved swinging members in said holders, substantially as shown and described.

4. A hinge comprising two similar holders having parallel tops and bottoms the ends of which are provided with oppositely-directed face-plates between which are openings the dimensions of which are similar to the dimensions of the holders in cross-section, and curved swinging members pivoted within said openings adjacent to the face-plates and adjacent to the corresponding sides of the holders when the latter are placed face to face, the said curved swinging members being crossed, and the curved swinging member pivoted in one holder being free to turn and swing in the other holder, and means for guiding the movements of said curved swinging members in said holders and for limiting the same, substantially as shown and described.

5. A hinge, comprising two holders having parallel tops and bottoms provided at their ends with oppositely-directed face-plates between which are openings, the dimensions of which are similar to the dimensions of the interior of the holders in cross-section, and curved swinging members pivoted within said openings adjacent to the face-plates and at the corresponding sides of the holders when the latter are placed face to face, the curved swinging members being crossed, and the curved swinging member which is pivoted in one holder being free to turn in the other holder, and means for guiding the movements of said curved swinging members in said holders and for limiting the same consisting of slots or grooves formed in the holders and pins connected with the curved swinging members and movable in said slots or grooves, substantially as shown and described.

In testimony that I claim the foregoing as my invention I have signed my name, in presence of the subscribing witnesses, this 12th day of April, 1905.

JOSEPH SOSS.
